UNITED STATES PATENT OFFICE.

GILMAN C. HILL, OF WATERBURY, CONNECTICUT, ASSIGNOR TO THE
WATERBURY BRASS COMPANY, OF SAME PLACE.

STUB-HOLDER.

SPECIFICATION forming part of Letters Patent No. 427,511, dated May 6, 1890.

Application filed December 13, 1889. Serial No. 333,675. (No model.)

To all whom it may concern:

Be it known that I, GILMAN C. HILL, a citizen of the United States, and a resident of Waterbury, in the county of New Haven and 5 State of Connecticut, have invented new and useful Improvements in Stub-Holders; and I do hereby declare the following to be a full, clear, and exact description of said invention, reference being had to the accompanying 10 drawings, and to the letters of reference marked thereon, which form a part of this specification.

My invention has for its object to provide an improved and simplified stub-holder, which 15 is designed more particularly for use in connection with books from which sections are to be torn or separated, leaving a stub or slip at the inner margin to preserve a memorandum of the separated portion; and my improvements consist, essentially, of a metallic spring-arm, the one end of which is pivotally secured to the inside cover of the book, while the opposite free end is adapted to project over and upon the stub or stubs to hold the 25 same in position, all as will be hereinafter more fully described, and specifically designated in the claims.

In the accompanying drawings, Figure 1 represents a top plan view of my improved device in operative position within a book, and 30 Fig. 2 a detail sectional view thereof.

Similar letters of reference indicate like parts in both figures of the drawings.

In carrying out my invention the spring-arm A is preferably formed of stout wire bent in the shape of an elongated loop, although the said arm may be constructed of sheet metal to secure the desired result without departing from the spirit of my invention.

40 The one end of the spring-arm A is secured to lugs or projections B, either formed integral with or otherwise suitably attached to a plate C, which in its turn is pivotally secured to a base-plate D by means of an eyelet or 45 rivet E, while the opposite or free end of the spring-arm is adapted to project the desired

distance over and upon the stub or stubs F, as fully shown in Fig. 1 of the drawings.

The base-plate D is adapted to be secured to the inner side of the cover G of the book 50 H by rivets, projecting spurs, or other suitable means.

The construction of my improved stub-holder being substantially as above described, it will be observed that in the operation of 55 the same the free end of the spring-arm is swung around, over, and upon the stub or stubs to hold the same down flat to insure of convenience and ease in filling up adjoining pages, or for the purpose of footing up memoranda upon the consecutive stubs, the said 60 spring-arm being swung around so as to lie flat upon the inner cover of the book when not in use, as fully shown in dotted lines in Fig. 1. 65

I do not confine myself to the precise construction shown and described, as it is apparent that changes may be made or equivalents substituted without materially affecting or altering the essential features of my invention. 70

Having thus described my invention, what I claim as new and useful, and desire to secure by Letters Patent, is—

1. A stub-holder consisting of a spring-arm the one end of which is pivotally secured 75 to the inside cover of a book, while the opposite free end is adapted to engage with the stub or stubs, substantially in the manner and for the purpose specified.

2. A stub-holder consisting of a spring-arm A, the one end whereof is secured to a plate and said plate pivotally connected to a base-plate for attachment to the inside cover of a book, substantially as and for the purpose specified. 80

85 In testimony whereof I affix my signature in presence of two subscribing witnesses.

GILMAN C. HILL. [L. S.]
